BATHING POOL

Merle C. Melchior, Los Angeles, Calif., assignor to Hydro-Spa, Inc., Sherman Oaks, Calif.

Filed Jan. 18, 1974, Ser. No. 434,433

Term of patent 14 years

Int. Cl. D23—02

U.S. Cl. D83—1 C

FIG. 1

FIG. 2

FIG.3

FIG.4

FIG.5

FIG. 1 is a perspective view of a bathing pool illustrating the new design.

FIG. 2 is a plan view thereof.

FIGS. 3, 4 and 5 are sectional views thereof taken in the planes 3—3, 4—4 and 5—5 respectively of FIG. 2.

I claim:

The ornamental design for a bathing pool, as shown.
